RING DOUBLING OR TWISTING MACHINES

Frank Ridgway, Stockport, England, assignor to Arundel Coulthard & Company Limited, Stockport, England, a British company

Application February 7, 1955, Serial No. 486,651

Claims priority, application Great Britain
February 22, 1954

5 Claims. (Cl. 57—120)

This invention relates to ring doubling or twisting machines and is concerned more particularly with the rings of such machines.

It is a usual practice to lubricate the rings by capillarity using wicks, each of which extends from an oil bath to a groove in the ring face where the traveller removes oil from the wick and distributes it around the ring face.

The object of my present invention is to provide improved ring lubricating means which enable higher spindle and therefore traveller speeds to be attained without the liability of brassing of the rings.

The invention consists in a ring doubling or twisting machine in which each ring is lubricated by a wick extending from an oil trough to a groove in the ring face, characterized in this that the up and down movement of the ring rail operates a reciprocatory pump which supplies oil to said trough.

The invention further consists in a ring doubling or twisting machine as aforesaid having a pumping device connected to the ring rail which in one direction of movement of such rail delivers oil into the trough in or on the ring rail so that the said trough is flooded temporarily and the wicks give a copious supply to the rings, and in the other direction of movement returns surplus oil from the trough for repumping.

The invention further consists in a ring doubling or twisting machine as aforesaid in which a tube extends at its upper end into said trough where it is secured to the ring rail and at its lower end constitutes a piston in a fixed cylinder closed at its lower end, such cylinder receiving surplus oil draining from the rings through a filter in a reservoir which moves with the ring rail and has a drain tube connected to the reservoir and to the cylinder.

The invention further consists in a ring doubling or twisting machine as aforesaid, in which one end of each wick extends into the trough and the other end into the reservoir at a level lower than the upper end of the drain tube connected to the reservoir.

The invention further consists in a ring doubling or twisting machine as aforesaid, in which the trough is connected to a supplementary oil receptacle which is supplied from the trough and has a plunger therein by which its contents can be returned to the trough to flood the same temporarily.

The invention further consists in a ring doubling or twisting machine as aforesaid, in which the ring rail has a recess therein below each ring to receive surplus oil from the ring and deliver it to the reservoir.

Referring to the accompanying explanatory drawings: Figure 1 is a sectional elevation on the line 1—1 of Figure 2, Figure 2 a plan view of Figure 1, Figure 3 a sectional elevation on the line 3—3 of Figure 2, Figure 4 a sectional elevation on the line 4—4 of Figure 2 and Figure 5 a sectional elevation on the line 5—5 of Figure 2 showing lubricating means for the rings of doubling or twisting machines constructed and arranged in one convenient form in accordance with this invention.

2

Figure 6 is a plan view and Figure 7 a sectional elevation on the line 7—7 of Figure 6 showing the oil filter used in the oil reservoir in Figures 1, 2 and 4.

Figures 8 and 9 are plan views of two clamps shown in Figure 1 to be hereinafter referred to.

Figure 10 is a view showing the lubricant pump of Figure 1 in the position in which the pump plunger is at the top of its stroke.

Figure 11 is a view similar to the upper part of Figure 10 but showing a modified arrangement.

Figure 12 is a sectional plan on the line 12—12 of Figure 11.

Figure 13 is a plan view of the oil filter shown in Figure 11.

Figure 14 is a sectional elevation on the line 14—14 of Figure 13.

Figure 15 is a plan view similar to the lower part of Figure 2 but drawn to a larger scale and showing the modified arrangement according to Figure 11.

Figure 16 is a sectional view on the line 16—16 of Figure 15.

In Figures 1—10, *a* indicates a length of ring rail with two rings *b* mounted therein in adapters *c* in a known manner; *d* are travellers on the rings.

Each ring has an oil groove *e* around its internal face with a wick *f* therein, the two ends of each wick being folded into a trough *g* formed in the ring rail *a*. A tube *h* which is secured in the ring rail in the manner shown to an enlarged scale in Figure 4 forms at its lower end a piston *i* moving in a closed bottom cylinder *j* secured at its upper end in the cap *k* of a cylinder *m* connected integrally with a lower cylinder *n* which is secured by a clamp *o* (see Figure 9) to a fixed guide sleeve *p* secured in the fixed girder *q*. A guide rod *r* known as a poker, is secured at its upper end to the ring rail and moves through the sleeve *p* as the ring rail is raised and lowered in the usual manner. There are holes *s* through the cylinder *j* within the cylinder *m*. A clamp *t* (see Figure 8) secures the tube *h* to a drain tube which moves in an outer tube secured in the cap *k* before referred to. The top of the tube *u* is secured to an annular oil reservoir *v* which has therein a filter *w* as shown in Figures 6 and 7. The top of the tube *u* comes below the level of the filtering material in the filter *w* so that only filtered oil flows down the tube *u* into the bottom of the fixed cylinder *n*. There is a supplementary oil receptacle at *y* in the ring rail (see Figure 1) with a plunger *z* therein which when depressed against the pressure of the spring *20* forces oil into the trough *g* to temporarily flood the wicks *f* in the trough.

Normally the cylinders *m*, *n* are filled with oil up to a level indicated at *21* in Figure 10 and this oil when the tube *h* with its piston *i* is in its raised position as shown in Figure 10 flows into the closed cylinder *j* which is filled thereby. As the ring rail *a* is lowered during the normal operation of the doubling or twisting machine, the hollow piston *i* first closes the holes *s* in the cylinder *j* and then displaces oil from said cylinder up the piston and over the top of the tube *h* so that such oil floods the trough *g* and the supplementary receptacle *y*.

It will be noted from Figures 3, 4 and 5 that the ring rail *a* is shaped at *23* to form a receptacle to receive oil dripping from the rings *b*, such oil flowing by tubes *24* to the oil reservoir *v* where it is filtered before passing down the tube *u* to the cylinder *n*.

When the oil trough *g* is full, the wicks *f* feed a surplus of oil to the inside of the rings which floods the grooves *e* in the rings. The travellers *d* as they revolve around the rings throw off surplus oil which drips from the rings and as shown in Figures 4 and 5 drips into the recesses *23* and drains into the reservoir *v* whence it returns by the tube *u* to the cylinder *n* for re-pumping.

If the doubling machine has been standing for some time so that the wicks have dried somewhat, the plunger *z* may be depressed to flood the wicks at starting up before the pump *i* moves downward to raise oil to the trough *g* and receptacle *y*.

When the ring rail is moved upwards, any surplus oil in the trough *g* above the level of the top of the tube *h* is drawn back into the pump cylinder.

The bottom of the cylinder *n* is closed by a plug which can be readily removed to clear the cylinder of any deposits. By releasing the clamps *t* and *o* the pumping unit can be lowered along the tube *h* so that the reservoir *v* and the filter *w* therein can be examined and cleaned.

In the arrangement shown in Figures 11-16, one end of each wick *f* which lubricates a ring *b* extends into a trough *25* but the other end of the wick passes down a tube *26* into the reservoir *v* where it comes above the filter material *w*. The drain tube *u* comes into a space *27* into which filtered oil only can pass and its upper end extends above the level of the filtering material on to which the ends of the wicks *f* extend through the tubes *26* so that such wick ends are always immersed in oil and serve by capillarity to supply oil at all times to the internal surface of the rings. This renders the plunger *z* of Figure 1 unnecessary for starting up purposes.

By my improvement, ring doubling and twisting machines with the larger diameters of rings are enabled to run at higher speeds than at present usual without brassing of the rings.

What I claim is:

1. In a twisting machine, a vertically reciprocable ring rail, rings carried by the ring rail, means defining a groove for each ring and a wick lodged in each groove, lubricating means therefor, such lubricating means including a trough associated with the ring rail with the wicks being in communication with the trough, a reciprocating pump piston carried by the ring rail, a fixed pump cylinder around said piston, the said piston serving to deliver lubricant to the trough in one direction of movement of the ring rail to flood the trough temporarily

whereupon the said wicks furnish a copious supply of lubricant to the rings, a reservoir movable with the ring rail, means to deliver surplus lubricant to the reservoir, and conduit means between the reservoir and the pump means to deliver the surplus lubricant to the pump means on movement of the ring rail in the other direction.

5 2. A twisting machine as defined in claim 1 wherein said pump means includes a tube secured to the ring rail and having its upper end opening in the trough, a hollow piston at the lower end of the tube, a fixed cylinder in which the piston operates having ports therein opened and closed by the piston, a filter in the reservoir and said conduit means comprising a drain tube in communication at one end with the reservoir below the filter and at the other end with the said fixed cylinder.

10 3. A twisting machine as defined in claim 2 wherein one end of each wick extends into the trough and the other end of each wick constitutes the means delivering surplus lubricant to the reservoir, with such other ends 20 extending into the reservoir at a level lower than the end of the drain tube within the reservoir.

4. A twisting machine as defined in claim 1 wherein the ring rail is provided with a supplementary lubricant receptacle communicating with and supplied by the trough and plunger means in the supplementary lubricant receptacle so that operation of the plunger means returns the lubricant in the receptacle to the trough to flood the trough temporarily.

5. A twisting machine as defined in claim 1 wherein 30 the means delivering surplus lubricant to the reservoir includes means defining a recess in the ring rail below each ring and tube means leading from the recess to the reservoir.
